To all whom it may concern:

Be it known that I, Harry A. Ganser, a citizen
of the United States of America, residing at No.
2255 Grand Concourse, New York city, county of
Bronx, and State of New York, have invented a
new, original, and ornamental Design for a
Coaster or Similar Article, of which the follow-
ing is a specification, reference being had to the
accompanying drawing, forming part thereof.

In the drawing:

Fig. 1 is a top plan view of the coaster embody-
ing the design; and

Fig. 2 is a side elevation thereof in cross-
section.

I claim:

The ornamental design for a coaster or similar
article, substantially as shown.

HARRY A. GANSER.
